(57) **CLAIM**

The ornamental design for a bulk cable dual gang wall plate, as shown and described.

DESCRIPTION

FIG. 1 is a perspective view of the bulk cable dual gang wall plate showing my new design, with the broken line showing the cable forming no part of the claimed design;

FIG. 2 is a side view thereof, with the opposite side being a mirror image thereof;

FIG. 3 is a top view thereof;

FIG. 4 is a front elevational view thereof;

FIG. 5 is a bottom view thereof; and,

FIG. 6 is a back view thereof.
